OF STOCKHOLM, SWEDEN.

AUTOMATIC CONTROL DEVICE FOR ILLUMINATING APPARATUS.

1,155,496.

Specification of Letters Patent.

Patented Oct. 5, 1915.

Application filed June 6, 1914. Serial No. 843,578.

To all whom it may concern:

Be it known that I, CARL GUSTAF LINDBLOM, a subject of the King of Sweden, residing at Lilla Essingen, Stockholm, Sweden, have invented new and useful Improvements in Automatic Control Devices for Illuminating Apparatus, of which the following is a specification.

The present invention has for its object to provide means for alternately lighting and extinguishing illuminating apparatus under the influence of reduced or increased supply of light and thus of heat. Said means consist substantially of a thermo-electric pile arranged within a transparent but to some extent heat-insulating casing and connected, either directly or through a relay, to a lighting and extinguishing apparatus, for instance a gas valve or an electric switch.

Two forms of the invention are illustrated in the accompanying drawing in vertical section in Figures 1 and 2.

The thermo-electric pile *a* in both cases is of cylindrical shape and has a comparatively great number of circular rows of elements arranged above each other, preferably also a rather great number in each circular row. It is surrounded by a casing *b* which is also cylindrical and preferably of glass. In Fig. 1 a heat-storing body *j* is arranged in the central cavity of the pile so as to be heat-insulated therefrom and not in direct communication with open air. The whole construction is arranged on a base *c* inclosing the lighting and extinguishing device proper. In Fig. 1 the last-mentioned device, which though is only diagrammatically illustrated, consists of an electromagnet *g* and an armature *d* actuated thereby and also serving as valve member for alternately closing and opening the mouth *h* of a gas conduit *f* leading to a burner. Part of the weight of the armature may be compensated by a spring *i* for facilitating its lifting by the magnet. The gas enters through a port *e*.

This apparatus operates in the following manner. As soon as the thermo-pile is subjected to radiation of light or heat from outside, for instance at sunrise if it is placed freely out-of-doors, the temperature of its external contact points is raised while the inner ones are kept at a lower temperature, partly by the body *j*, partly by rising air currents (see the arrows). The glass cas-

ing *b* prevents greater losses of heat in the case of wind, etc. The thermo-pile then produces an electric current which causes the electromagnet *g* to attract its armature *d*, said armature then closing the mouth *h* and thus cutting off the supply of gas to the burner so as to extinguish the flame thereof.

The armature *d* in Fig. 1 is supposed to be polarized for the reason of preventing its dropping which otherwise may occur when the difference of temperature between the inner and outer contact points of the thermo-pile are by and by equalized and the current thus weakened. When the supply of heat from outside ceases, for instance at sunset, in this form a difference of temperature arises in the opposite direction, the heat storing body *j* keeping the inner contact points at a comparatively high temperature while the outer ones are cooled. The current then is reversed and causes the dropping of the armature *d* so that the gas supply to the burner is again opened, lighting then being possible to effect by means of a pilot flame or in other ways. In Fig. 2 the heat storing body is omitted and the further modification is made that the thermo currents do not act upon the controlling device directly but by means of a relay. These two modifications, however, are of course quite independent of each other, so that a relay can be used together with the heat storing body and the latter may be omitted in directly acting devices according to Fig. 1. The current from the thermo-pile in Fig. 2 flows through a relay coil *k* actuating a light, non-polarized armature *l* which then closes a current from a battery *m* through a main coil *n* actuating a polarized armature *o*, which here is combined with a toggle-joint lever for facilitating an instantaneous reversing action. When the current of the thermo-pile ceases by the heat supply to its outer contact points ceasing, the armature *l* is dropped and a current thereby sent through the coil *n* in the opposite direction to the previous one, whereby the armature *o* is dropped and the conduit *f*, which has been closed by said armature, is opened.

Having now particularly described the nature of my invention and the manner of its operation, what I claim is:

1. A device for lighting and extinguishing illuminating apparatus comprising an electric thermo-pile, one group of like-poled

contact points of which is exposed to the action of day-light, a transparent heat insulating casing surrounding said thermo-pile, a conductor for a light producing medium, and means actuated by the current from said pile for controlling the passage of the light producing medium through said conductor.

2. A device for lighting and extinguishing illuminating apparatus comprising an electric thermo-pile, one group of like-poled contact points of which is exposed to the action of day-light while the other group is exposed to a current of air, a transparent heat insulating casing surrounding said thermo-pile so as to protect the first-named group of contact points against air currents, a conductor for a light producing medium, and means actuated by the electric current from the thermo-pile for controlling the passage of the light producing medium through said conductor.

3. A device for lighting and extinguishing illuminating apparatus comprising an electric thermo-pile, one group of like-poled contact points of which is exposed to the action of day-light, a heat storing body arranged adjacent to the other group of like-poled contact points, a transparent heat insulating casing surrounding said thermo-pile, a conductor for a light producing medium, and means actuated by the electric current from said pile for controlling the

passage of the light producing medium through said conductor

4. A device for lighting and extinguishing illuminating apparatus comprising an electric thermo-pile, one group of like-poled contact points of which is exposed to the action of day-light, a transparent heat insulating casing surrounding said thermo-pile, a conductor for a light producing medium, and a relay actuated by the current from said thermo-pile, said relay controlling the passage of the light producing medium through said conductor.

5. A device for lighting and extinguishing illuminating apparatus comprising an electric thermo-pile, one group of like-poled contact points of which is exposed to the action of day-light, a transparent heat insulating casing surrounding said thermo-pile, a conductor for a light producing medium, an electro-magnet actuated by the current from said thermo-pile, and a polarized armature operated by said electro-magnet and acting to control the passage of the light producing medium through said conductor.

In testimony whereof I have signed my name to this specification in the presence of two subscribing witnesses.

CARL GUSTAF LINDBLOM.
